DEVICE FOR GUARDING FINGER FROM APPLICATION OF NAIL POLISH

Joseph J. Smidl, Portland, Oreg.

Application January 31, 1949, Serial No. 73,707

4 Claims. (Cl. 132—88.5)

1

The present invention is a device for use in guarding against the application of nail polish to portions of the finger surrounding the nail. The principal object of the present invention is to provide such a device which may be used in conjunction with a wide range of different sizes and shapes of finger-nails.

A further object of the present invention is to provide such a device which may be used while resting upon a table or surface so that the brush-wielding hand may be entirely free to control the application of nail polish to the finger-nail.

The foregoing and other objects and advantages of the present invention will be more readily ascertained by inspection of the following specification taken in connection with the accompanying drawings wherein like numerals refer to like parts throughout, while the features of novelty will be more distinctly pointed out in the appended claims.

In the drawings

Fig. 1 is a plan view of a device made in accordance with my invention;

Fig. 2 is a side elevation of the device;

Fig. 3 is an end view of the device looking from the line 3—3 of Fig. 2;

Fig. 4 is a vertical section taken substantially along line 4—4 of Fig. 1;

Fig. 5 is a vertical section taken substantially along line 5—5 of Fig. 1;

Fig. 6 is a side elevation, on an enlarged scale, of a modified form of a portion of the device; and

Fig. 7 is a plan view of a guard element for use in the device.

The device comprises a base 10 which may be placed upon a table or other support, the base having a sloping upper surface terminating in a raised portion 11 upon which the tip of a finger may be placed as seen in dotted lines in Fig. 1, the edge of the raised portion providing means for locating the finger with respect to the device. A pair of uprights 12 are mounted upon the base forwardly of the portion 11, and a supporting plate 13 is pivotally mounted upon the uprights 12 as by means of screws 14 having their tips inserted in openings in the forward edge of the plate, the plate being thereby pivotally mounted upon the base along an axis extending transversely thereof. A first arm 15 extends longitudinally of the base above the portion 11, the arm curving upwardly away from the base. The arm is extended forwardly beneath the supporting plate 13 and curved about and secured to a transverse tubular bearing 16 mounted upon a

2

lateral guide rod 17, and is then directed rearwardly and secured to a tubular bearing 18 mounted upon a second guide 19 extending laterally of the base, the extremity of the arm, the rod 17 and the guide 19 preferably being secured together by a pin 20. The guides 17 and 19 are not secured to the base or the supporting plate but, as seen in Fig. 3, the guide 19 is of sufficient length to fit snugly between the uprights 12 whereby it is prevented from movement laterally of the base. The guides are supported against the lower surface of the supporting plate 13 by a leaf spring 21 bearing against the lower reach of the arm 15, the leaf spring being secured in position by a portion thereof passing beneath the base of the upright 12. As the arm 15 is raised relative to the base portion 11 by pressing downwardly on the plate 13, the spring 21 is pressed downwardly. It will be noted that the portion of the arm 15 is secured to the bearing member 16 and the bearing member 18 but is not secured to the plate 13. The portion of the arm 15 wrapped about the bearing member 18 may engage a portion of the base 10 when the plate 13 is depressed but this does not prevent movement of the plate since the entire structure may slide outwardly between the plate 13 and the leaf spring 21. The arm 15 is always resiliently pressed toward the base portion 11 by spring 21.

30 A second arm 25, similar to arm 15, extends beneath plate 13, passes about and is secured to a tubular bearing 26 slidably mounted on guide 17, and then passes forwardly and is secured to a tubular bearing 27 slidably mounted on rod 19.

35 A strap 29 is secured to the upper surface of the arm 25 adjacent the forward edge of plate 13, passes around the plate and is secured to the lower reach of arm 25 beneath the plate 13. A knob 31 is fixed to a portion of the strap 29 and may be grasped in order to slide the arm 25 along the guides 17 and 19. A spring 32 is extended between the portions of the arms 15 and 25 beneath the plate 13, the spring tending to draw the two arms toward each other.

40 45 A left finger guard 35 is secured to the lower surface of arm 15 by a plurality of longitudinally spaced screws 36, and a right finger guard 37 is secured to the lower surface of arm 25 by a plurality of screws 38. The finger guards are preferably made of sheets of transparent material which tend to lie in a flat plane, and the screws are tightened to cause the finger guards to conform to the curvature of the arms whereby the forward extremities thereof are closer to the base 50 than the rear portions which extend over the

finger behind the finger-nail. The guards could be made of opaque, resilient sheet material, but it is preferred that they be transparent so that the operator may be certain of properly placing them with respect to the finger-nail.

The foregoing form of the device may be used with a wide range of finger-nails by shaping the arms to conform to the fingers of the person and by shaping the guards to conform to the outline of the type of finger-nail of the user. However, in order that the device may be used with a plurality of different types of finger-nails without bending the arms or changing the guards, I prefer to have the guards mounted upon upwardly curved arms such as the arm 40, illustrated in Fig. 6, by means of a plurality of longitudinally spaced screws 41 passing through holes in the guard, the screws being of sufficient length to permit considerable regulation of the curvature of the guard. I also prefer that the screws pass through openings 42 in the guards, of considerable diameter with respect to the diameter of the screws 41, so that the guards may be shifted about with respect to the arms.

Having illustrated and described preferred embodiments of the invention, it should be apparent to those skilled in the art that the invention permits of modification in detail and arrangement. I claim as my invention all such modifications as come within the true spirit and scope of the appended claims.

I claim:

1. A device for use in guarding against the application of nail polish to portions of the finger surrounding the nail, comprising a base upon which to rest the finger, a supporting plate pivotally mounted on said base for movement about an axis extending transversely thereof, guiding means on said supporting plate parallel to the axis of pivotal movement, a first arm mounted on said supporting plate and projecting over said base, a second arm slidably mounted on said guiding means and projecting over said base, first resilient means urging said supporting plate in a direction to depress said arms toward said base, second resilient means urging said second arm toward said first arm, and opposed finger guards mounted on said arms, each of said finger guards comprising a member adapted to overlie the fleshy portions of the finger at a side and the base of the fingernail to prevent the application of nail polish thereto.

2. A device for use in guarding against the application of nail polish to portions of the finger surrounding the nail, comprising a base upon which to rest the finger, a supporting plate pivotally mounted on said base for movement about an axis extending transversely thereof, guiding means on said supporting plate parallel to the axis of pivotal movement, a first arm mounted on said supporting plate and projecting over said base, a second arm slidably mounted on said guiding means and projecting over said base, first resilient means urging said supporting plate in a direction to depress said arms toward said base, second resilient means urging said second arm toward said first arm, opposed finger guards mounted on said arms, each of said finger guards comprising a member adapted to overlie the fleshy portions of the finger at a side and the base of the fingernail to prevent the application of nail polish thereto, said arms being curved upwardly

from said base toward their free ends, and said finger guards being formed of resilient material tending to lie in a flat plane, and adjustable means urging said guards to conform to the curvature of said arms.

3. A device for use in guarding against the application of nail polish to portions of the finger surrounding the nail, comprising a base upon which to rest the finger, a supporting plate pivotally mounted on said base for movement about an axis extending transversely thereof, guiding means on said supporting plate parallel to the axis of pivotal movement, a first arm mounted on said supporting plate and projecting over said base, a second arm slidably mounted on said guiding means and projecting over said base, first resilient means urging said supporting plate in a direction to depress said arms toward said base, second resilient means urging said second arm toward said first arm, opposed finger guards mounted on said arms, each of said finger guards comprising a member adapted to overlie the fleshy portions of the finger at a side and the base of the fingernail to prevent the application of nail polish thereto, said arms being curved upwardly from said base toward their free ends, and said finger guards being formed of resilient material tending to lie in a flat plane, and a plurality of screws joining said finger guards to said arms at a plurality of longitudinally spaced points along said arms.

4. A device for use in guarding against the application of nail polish to portions of the finger surrounding the nail, comprising a base upon which to rest the finger, a supporting plate pivotally mounted on said base for movement about an axis extending transversely thereof, guiding means on said supporting plate parallel to the axis of pivotal movement, a first arm mounted on said supporting plate and projecting over said base, a second arm slidably mounted on said guiding means and projecting over said base, first resilient means urging said supporting plate in a direction to depress said arms toward said base, second resilient means urging said second arm toward said first arm, opposed finger guards mounted on said arms, each of said finger guards comprising a member adapted to overlie the fleshy portions of the finger at a side and the base of the fingernail to prevent the application of nail polish thereto, said arms being curved upwardly from said base toward their free ends, and said finger guards being formed of resilient material tending to lie in a flat plane, and a plurality of fastening means joining each of said finger guards to one of said arms at a plurality of longitudinally spaced points along said arms, said fastening means comprising screws threadedly engaging said arms, and said guards having enlarged openings through which said screws pass to permit relative adjustment of said guards and arms.
